ABSTRACT: The credit card holder includes a string of independent, transparent envelopes interconnected by flexible tapes. The tape arrangement permits the envelopes to hang vertically and by rotating the upper end envelope laterally through a half turn, each of the successive depending envelopes is rotated in sequence so that front and rear faces are juxtaposed throughout the string. The tape arrangement also permits the folding of the envelopes into a compact, closed condition in which each envelope may be rotated about a common end and the faces of each envelope may thereby be viewed consecutively. A cover holds the envelopes together in the folded condition and facilitates manipulation of the upper end envelope in the vertically extended condition.

CREDIT CARD HOLDER

BACKGROUND OF THE INVENTION

This invention relates in general to a foldout container for displaying cards of an identifying nature, and in particular to a pocket-size holder having the character of a billfold for credit cards, membership cards and other documents of a similar size.

Foldout containers in the prior art fall generally into two categories: those which comprise a plurality of transparent envelopes formed from a continuous double thickness strip, heat sealed at intervals to form the individual envelopes and those in which the interconnection between individual envelopes is by means of tapes continuous over several panels. Devices falling into the first category provide a hinge connection between envelopes which tends to be stiff. Those in the second category tend to be complicated and therefore somewhat expensive.

In the usual holder, the transparent envelope used permits a double display of back-to-back cards. However, because of the continuous end-to-end connection between adjacent envelopes, only one face of each envelope is visible as the foldout is leafed through. The envelopes must be turned over and leafed through once more to view the other face of each envelope.

SUMMARY OF THE INVENTION

The foldout container of this invention includes flexible, interconnecting tape elements which provide a direct connection between abutting edges of adjacent envelopes.

The envelopes may be held vertically in an open condition and simply by rotating the upper envelope a half turn about a lateral axis, each of the subjacent envelopes is rotated consecutively and automatically, until each envelope is juxtaposed and the rear faces are displayed.

In the folded condition, the string of interconnected envelopes may be leafed through like pages of a book and each face of adjacent envelopes may be viewed consecutively.

The holder includes a string of independent, transparent envelopes adapted to display credit cards. The envelopes are interconnected by first and second tape means, the arrangement of which permits the envelopes to be folded together into an overlying relation to form a compact unit, or to be held in a strung out condition in which the envelopes are disposed edge-to-edge substantially vertically in an open condition. Two open conditions are possible. In the first, the front face of each envelope is displayed and in the second, the rear face of each envelope is displayed.

In the first open condition, a first tape means interconnects the top edges of adjacent envelopes and a second tape means interconnects the bottom edges of adjacent envelopes. When the envelopes are held in the strung out condition, rotation of the upper end envelope about a lateral axis causes a chain reaction of rotating the other envelopes sequentially from the first open condition to the second open condition.

A cover, including a back and adjacent side panels, holds the envelopes in the closed, folded condition. The upper end envelope is attached to the back of the cover, and the side panels may be bent forwardly over the compact, folded envelope unit and fastened together to maintain the envelopes in the folded condition. The side panels of the cover may also be bent backwardly to a digital grip position to facilitate manipulation of the upper end envelope between the first and second open conditions of the envelope string. In order to facilitate the bending of the cover, the side panels are hingedly attached to the back. The upper end envelope is preferably detachably attached to the back of the cover.

The first tape means includes a plurality of individual tapes extending across each envelope except for the lower end envelope in the first open condition; and each envelope except for the upper end envelope, in the second open condition. The second tape means includes a plurality of individual tapes ex-

tending across each envelope except the upper end envelope, in the first open condition; and each envelope except the lower end envelope in the second open condition. One of the tape means includes a first set of vertically aligned tape elements passing over the front face of alternate envelopes and a second set of vertically aligned tape elements passing over the rear face of adjacent alternate envelopes. The other tape means includes a first set of vertically aligned tape elements passing over the front face of alternate envelopes, and a fourth set of substantially vertically aligned tape elements passes over the rear face of adjacent alternate envelopes. Each tape element passes over one face of an envelope and is attached to the rear face of that envelope and the rear face of an adjacent envelope.

The tape arrangement permits the envelopes to be turned in the manner of pages of a book, front and rear faces of each envelope being viewed consecutively.

BRIEF DESCRIPTION OF THE DRAWING

FIG. 1 is a perspective view of the credit card holder illustrating the envelopes in an open condition;

FIG. 2 is a perspective view of the credit card holder illustrating the envelopes in another open condition after rotation of the cover;

FIG. 3 is a fragmentary, enlarged side elevational view taken on lines 3-3 of FIG. 1;

FIG. 4 is a fragmentary, enlarged side elevational view partly in cross section, taken on lines 4-4 of FIG. 1;

FIG. 5 is an enlarged perspective view illustrating the credit card holder in the folded condition, and

FIG. 6 corresponds to FIG. 1 and is an exploded view illustrating a modified connection of the cover to the upper end envelope.

DESCRIPTION OF THE PREFERRED EMBODIMENT

Referring now by characters of reference to the drawing and first to FIG. 1, it will be understood that the credit card holder includes a string 10 of independent, yet interconnected, transparent envelopes. The string 10 includes a plurality of transparent envelopes 11 through 16. It will be understood that the device is not limited to six envelopes and this number is shown merely by way of illustration.

Each of the envelopes 11 through 16 includes associated front and rear faces. The front and rear faces, for convenience, are referred to by the reference numeral denoting the envelope, together with the suffix *a* or *b* respectively.

Each of the envelopes 11 through 16 includes an opening along one side to admit at least one credit or identification card for display within associated envelope. Two such credit cards per envelope are indicated by numerals 40 in FIGS. 3 and 4. The envelopes may be made by heat sealing the edges of a pair of plastic panels or by any other suitable method known to those skilled in the art.

The first or upper end envelope 11 is attached to a cover 30. The envelopes 11 through 16 are interconnected by a flexible tape arrangement constituting first and second tape means, to permit each envelope to fold freely against each adjacent envelope in the manner illustrated in FIG. 5. The side panels 33 of the cover 30 are adapted to be folded over the compact envelope unit.

A plurality of individual tapes constituting the first tape means interconnects the top edges of adjacent envelopes in a first open condition as illustrated in FIG. 1, and includes first and second sets of tapes. The first set of tapes comprises substantially centrally aligned single tapes 20, 21 and 22, each tape having an elongate portion passing freely over the front faces respectively of alternate envelopes 11, 13 and 15; and end portions attached to the rear faces respectively of envelopes 11, 12; 13, 14; and 15, 16. The second set of tapes comprises substantially aligned pairs of tapes 23 and 24, each such tape having an elongate portion passing freely over the rear faces respectively of envelopes 12 and 14, and end por-

tions attached to the front faces respectively of envelopes 12, 13; and 14, 15.

A plurality of individual tapes constituting the second tape means interconnects the bottom edges of adjacent envelopes in a first open position as illustrated in FIG. 1, and includes third and fourth sets of tape. The third set of tapes comprises substantially aligned pairs of tapes 25, 26 and 27, each such tape having an elongate portion passing freely over the front faces respectively of envelopes 12, 14 and 16, and end portions attached to the rear faces respectively of envelopes 11, 12; 13, 14; and 15, 16. The fourth set of tapes comprises substantially centrally aligned single tapes 28 and 29, each such tape having an elongate portion passing freely over the rear faces respectively of envelopes 13 and 15, and end portions attached to the front faces respectively of envelopes 12, 13; and 14, 15.

Typical tape arrangements are clearly illustrated in FIGS. 3 and 4. It is to be understood that although FIG. 3 specifically illustrates an elevation on envelope 12, FIG. 1, like elevations on envelope 14, FIG. 1 and envelopes 13 and 15, FIG. 2 would illustrate a similar tape arrangement to that shown in FIG. 3. Likewise, FIG. 4 specifically illustrates a sectional elevation on envelope 13, FIG. 1. However, like elevations on envelopes 15, FIG. 1 and envelopes 12 and 14, FIG. 2 would illustrate a similar tape arrangement.

FIG. 1 illustrates the envelopes and the string 10 in a first open condition wherein the front face of each envelope is presented for viewing. Because of the arrangement of tapes described above, the rotation of the first end envelope 11 in a clockwise direction, as shown by the arrows, through a half turn causes a chain reaction rearrangement of the tapes. In consequence of the chain reaction arrangement of the tapes, each of the succeeding envelopes is released and rotated in sequence through a half turn. The envelopes are thus juxtaposed into a reversed position so that the rear face of each is presented for view. The string 10 is then in a second open condition as shown in FIG. 2.

In the second open condition, because of the rotation of each envelope, the tapes of the first tape means, which formerly connected the upper ends of adjacent envelopes, now connect the lower ends of adjacent envelopes. Likewise, the tapes of the second tape means now connect the upper ends of adjacent envelopes. In other words, the first and second sets of tapes 20, 21, 22; and 23, 24 respectively now extend across the face of superjacent envelopes relative to the first open condition. Also, the third and fourth sets of tapes 25, 26, 27; and 28, 29 respectively now extend across subjacent envelopes relative to the first open condition.

The cover 30 to which the first end envelope 11 is attached includes a back panel 31 and side panels 32 and 33. The side panels 32 and 33 overlap in the closed position as may be ascertained from a consideration of FIG. 5. The side panels 32 and 33 are provided with interfitting snap fasteners 35 and 36 to facilitate the holding together of the envelopes as a compact, folded unit in the closed condition. In the preferred embodiment, the side panels 32 and 33 are connected to the back 31 by piano-type hinges 34. This form of connection facilitates the bending of the side panels 32 and 33 backwards to a position where they may be conveniently gripped digitally. When thus held, the cover 30 and the attached first end envelope 11 may easily be oscillated through the half turns by a flick of the wrist.

The first end envelope 11 may be attached by an adhesive means to the cover 30. If the cover 30 is of the same material as the envelopes, it may even be heat sealed into an integral relationship with the end envelope 11. However, in the preferred embodiment, the end envelope 11 is detachable from the cover 30 because this facilitates the placement of refill envelopes.

FIG. 6 illustrates a detachable connection between the end envelope 11 and the cover 30. It will be observed that the back 31 of the cover 30 is slit along four parallel lines to provide a pair of loops 37. An attachment element 41 is provided in the

end envelope 11. The attachment element 41 includes bendable tabs 42, and in the embodiment shown, both vertical sides of the end envelope 11 are open sufficiently to allow the tabs 42 to project therefrom. By threading each of the tabs 42 to an associated loop 37, the attachment of the end envelope 11 to the cover 30 is quickly accomplished.

FIG. 5 illustrates the credit card holder in a partially folded condition. It will be observed that the tape arrangement is such that each envelope, as for example, envelope 14, may be turned about a common end as though it were a page in a book. Each face of the envelopes may thus be viewed in sequence and, in the usual case where a pair of credit cards is placed back-to-back in each envelope, this means that every credit card may be observed as the envelopes are leafed through successively. In the usual foldout of continuous envelopes, this is not possible. All of the front faces of a string of envelopes must be leafed through first, and then the process must be reversely repeated to view all of the rear faces.

Further, although in FIG. 5, the envelopes are shown as though the leafing process were from left to right, with the right side acting, as it were, as the spine of a book, the leafing could just as well be commenced from right to left. In such a case, the left side of the folded unit would act as the book spine. Whichever way is chosen, both faces of each envelope will be viewed consecutively as with pages of a book.

It is thought that the functional advantages of this credit card holder will have become fully apparent from the foregoing description of parts, but for completeness of disclosure, the usage of the holder will be briefly described.

Each transparent envelope of the string 10 is of a size to accommodate preferably at least two credit cards 40 as shown in FIGS. 3 and 4. It will be understood, of course, that only the front face of the end envelope 11 will be exposable when a cover 30 is provided.

The tapes which interconnect the independent envelopes are of a sufficiently flexible material so that when the cover 30 is opened, the string of envelopes will fall into a substantially vertical relationship as indicated in FIGS. 1 and 2. In the ordinary folder of continuous envelopes, the reverse face of each envelope is presented by rotating the string about its vertical axis. With the arrangement of tapes illustrated in FIG. 1, however, a flick of the wrist rotating the cover 30 and attached end envelope 11 about a lateral axis sets off a chain reaction which automatically reverses each envelope in succession.

When it is desired to leaf through the envelopes individually, the cover 30 may be opened by unsnapping the overlapping side panels 32 and 33, and the front and rear faces of each envelope viewed consecutively as illustrated in FIG. 5 by turning each envelope exactly as though it were a page in a book.

I claim:

1. A holder for credit cards and the like comprising:
  - a. a plurality of independent, transparent envelopes the envelopes being adapted to display credit cards;
  - b. means interconnecting the envelopes in overlying relation in a closed, folded condition and in substantial edge-to-edge relation in a first open condition, the interconnected envelopes having a first end envelope and an opposite second end envelope, said interconnecting means including:
    1. a first tape means interconnecting the top edges of adjacent envelopes in the first open condition; and
    2. a second tape means interconnecting the bottom edges of adjacent envelopes in the first open condition;
    - c. the first open condition displaying the front face of each envelope; and
    - d. rotation of end envelope about a lateral axis while in the first open condition causing a chain reaction of flipping each successive adjacent envelope to a second, open condition displaying the rear face of each envelope.
  2. A credit card holder as defined in claim 1, in which:
    - e. the envelopes are rotatable about a common end while in the closed condition so that the face of each envelope may be viewed consecutively.

3. A credit card holder as defined in claim 1, in which:
 e. cover means holds the envelopes together in the closed condition, the cover means including a back portion attached to the first envelope to facilitate rotation of the first end envelope from the first open condition to the second open condition.
4. A credit card holder as defined in claim 3, in which:
 f. the cover means includes front portions disposed in overlapping relation in the closed condition and bendable back to a digital grip position in the open condition.
5. A credit card holder as defined in claim 1, in which:
 e. cover means holds the envelopes together in the closed condition, the cover means including a back portion and adjacent side panels hingedly attached to the back portion; and
 f. the back portion being detachably attached to the first end envelope, and the side panels being bendable back to a digital grip position in the open condition.
6. A credit card holder as defined in claim 1, in which:
 e. the first tape means extends across each envelope except the second end envelope in the first open condition and each envelope except the first end envelope in the second open condition, and
 f. the second tape means extends across each envelope except the first end envelope in the first open condition and each envelope except the second end envelope in the second open condition.
7. A credit card holder as defined in claim 1, in which:
 e. one of said tape means includes:
   1. a first set of substantially vertically aligned tape elements passing over the front face of alternate envelopes; and
   2. a second set of substantially vertically aligned tape elements passing over the rear face of intermediate, alternate envelopes;
8. A credit card holder as defined in claim 7, in which:
 f. the other of said tape means includes:

1. a third set of substantially vertically aligned tape elements passing over the front face of alternate envelopes; and
 2. a fourth set of substantially vertically aligned tape elements passing over the rear face of intermediate, alternate envelopes;
9. A credit card holder as defined in claim 7, in which:
 f. tape elements passing over one face of an envelope are attached to the other face of that envelope and the other face of an adjacent envelope at the edges of said other faces.
10. A credit card holder as defined in claim 1, in which:
 e. each of said tape means includes alternating single and double tape elements in the first and second open condition, the single tape elements being disposed substantially centrally of the double tape elements.
11. A credit card holder as defined in claim 1, in which:
 d. the first tape means in the first open condition includes:
 1. a first set of substantially vertically aligned single tape elements passing over the front face of alternate envelopes and attached to the rear face of those envelopes and the rear face of subadjacent envelopes; and
 2. a second set of substantially vertically aligned pairs of tape elements passing over the rear face of alternate envelopes, and attached to the front face of those envelopes and the front face of subjacent envelopes;
- f. the second tape means in the first open condition includes:
 1. a third set of substantially vertically aligned pairs of tape elements passing over the front face of alternate envelopes and attached to the rear face of those envelopes and the rear face of superjacent envelopes, and
 2. a fourth set of substantially vertically aligned single tape elements passing over the rear face of alternate envelopes, and attached to the front face of those envelopes and the front face of superjacent envelopes.
